UNITED STATES PATENT OFFICE.

DOMINICK CLÉRICO, OF YONKERS, NEW YORK.

COVER AND DOOR FOR VAULTS, &c.

No. 799,303.

Specification of Letters Patent.

Patented Sept. 12, 1905.

Application filed December 21, 1904. Serial No. 237,740.

To all whom it may concern:

Be it known that I, DOMINICK CLÉRICO, a citizen of the United States, and a resident of Yonkers, in the county of Westchester and State of New York, have invented certain new and useful Improvements in Covers and Doors for Vaults and the Like, of which the following is a specification.

The invention relates to improvements in covers and doors for vaults and the like; and it consists in certain novel features herein-after described and claimed pertaining to the glass lights and means for securing the same in place.

The door or cover is usually a plate, either cast or sheet metal, containing a number of holes in which the glasses are secured, and heretofore difficulties and inconveniences have been experienced in properly securing these glasses in position.

The object of my invention is to provide a new construction of glass and securing means whereby the glass may be very readily and quickly applied to position in the plate and, if found necessary, removed therefrom.

In carrying out my invention I provide the plate, if it be of cast metal or of sufficient thickness, with a series of holes whose walls are screw-threaded and taper inwardly, and around each of these holes at the outer side of the plate I recess the latter to receive the edges of the outer ends of the glasses. Each of the glasses is formed with an outer end or head and an inner flanged end, and between said head and the flanges of said inner end is formed an annular groove to receive a split locking-ring whose outer externally-threaded edges are tapered correspondingly with the holes in the plate. The inner edge of the locking-ring is formed with lugs to engage recesses formed within the grooved portion of the glass, and the glass at its inner end is formed with a polygonal recess to receive a key whereby to screw the glass with the ring thereon into the threaded hole in the plate, the said lugs and recesses preventing the glass from turning within the ring.

When the plate is of sheet metal or too thin to be recessed and threaded at the holes therein to directly receive the glass and its externally-threaded securing-ring, I provide a separate cast-metal ring internally and externally threaded and adapted to the hole in the sheet-metal plate and utilize this ring to receive the glass and its securing-ring.

The invention will be fully understood from

the detailed description hereinafter presented, reference being had to the accompanying drawings, in which:

Figure 1 is a top view of a portion of a cast-metal cover or door provided with a series of recesses and threaded holes to receive the glasses and their externally-threaded locking-rings. Fig. 2 is a section of same on the dotted line 2-2 of Fig. 1. Fig. 3 is a detached top view of one of the glasses. Fig. 4 is an edge elevation, partly broken away, of same. Fig. 5 is a detached top view of the locking-ring for the glass shown in Figs. 3 and 4. Fig. 6 is a section of same on the dotted line 6-6 of Fig. 5. Fig. 7 is a top view of a portion of the cover-plate or door with the glass secured therein. Fig. 8 is a section of same on the dotted line 8-8 of Fig. 7. Fig. 9 is a top view of a sheet-metal cover or door provided with a series of threaded holes to receive a specially-constructed externally and internally threaded ring adapted to receive the glass and locking-ring of my invention. Fig. 10 is a section of same on the dotted line 10-10 of Fig. 9. Fig. 11 is a top view of a portion of the sheet-metal plate with the externally and internally threaded ring therein, and Fig. 12 is a section of same on the dotted line 12-12 of Fig. 11.

I will first describe the construction illustrated in Figs. 1 to 8, inclusive, this construction comprising a thick or cast-metal plate to receive the glasses, and then the construction shown in Figs. 9 to 12, inclusive, the plate 90 there presented being thin or of sheet metal and requiring an extra ring for each hole, as shown in Fig. 12, to receive the glasses and their rings.

Referring to Figs. 1 to 8, inclusive, 15 designates the plate, having a series of holes 16, which are internally threaded and surrounded by recesses 17. The walls of the holes 16 taper inwardly, as more clearly shown in Fig. 8, and the recesses 17 extend laterally of the holes 16 and are of sufficient depth to receive the outer edges of the glasses 18, so that the outer surface of the cover shall be reasonably smooth and the edges of the glasses may be protected. The plate 15 therefore 105 may be of any suitable size and material and is provided with the series of threaded tapered receiving-holes 16, each surrounded at its outer end by a recess 17. The glass 18 for each of the holes of the plate comprises 110 an outer end or head 19, an inner end 20, having an annular laterally-extending flange 21,

and an annular groove 22, formed between the flange 21 and the flanged head 19. The inner end 20 of the glass is also formed with a polygonal recess 23 to receive a key or other instrument for screwing the glass and its locking-ring 24 into the hole 16 of the plate 15, as hereinafter explained. Within the annular groove 22 of the glass 18 are formed one or more (preferably two) recesses 25 to receive 5 and coöperate with the lugs or ribs 26, provided on the inner edges of the locking-ring 24, which, as shown in Figs. 5 and 6, is a split ring and is of metal. The ring 24 has its outer edges screw-threaded and tapered correspondingly with the taper of the holes 16. The ring 24, owing to its being split, may be sprung over the flange 21 at the inner end of the glass 18, so that said ring may lie between said flange and the flanged head 19 and snugly 10 fit the groove 22, encompassing said glass. In Figs. 5 and 6 I illustrate the ring 24 as detached from the glass 18, and in Fig. 8 I illustrate the same in position upon the glass and the whole secured in the plate 15. In applying 15 the ring 24 upon the glass the ribs or lugs 26 thereon will be caused to enter the recesses 25 in the glass, so that the ring and glass may be locked together and said ring be compelled to turn with the glass when the latter is rotated during its application to or removal 20 from the plate 15. The plate 15 having been provided with the threaded tapered holes 16 and recesses 17 and the glasses 18 having had the rings 24 applied upon them, the said glasses 25 are screwed into said holes until the edges of the heads 19 become firmly seated within the recesses 17. The glasses 18 pass into the holes 16 from the outer side of the plate and may be firmly screwed home from the inner side of said plate by means of a key or like instrument applied to the recess 23. The glasses 18 may also be removed from the plate by unscrewing the same therefrom from the inner side of the plate. The joints about the 30 holes 16 may be rendered liquid-tight by the application of white lead to the parts before the glasses are secured in position. It will be observed that the inner end of the glass 18 is less in diameter than the holes 16, and that 35 hence no difficulty will be experienced in introducing the glasses from the outer side of the plate and compelling the threaded ring 24 to engage the threaded walls of said holes. In the construction presented the ring 24 is 40 formed with the ribs 26 and the glass with the recesses 25; but it is obvious that the ribs might be on the glass and the recesses on the ring with like effect. I regard the ribs 26 and recesses 25 as merely lugs to engage each 45 other and compel the ring to turn with the glass during the application of the latter to or its removal from the holes 16. The glass 18 cannot well be threaded, and hence I apply the threaded ring 24 thereto, so that it 50 may engage the threaded walls of the holes

16. The fact that the ring 24 fits within the annular groove of the glass prevents the latter from slipping from the ring, and when the glass and ring are in position in the hole 16 the walls of the latter firmly bind the ring, and at such time the glass cannot escape from the plate.

There may be occasions when it may be desired to apply the glass and its ring to sheet-metal plates or other plates too thin to permit the direct formation therein of the tapered threaded holes 16 and recesses 17, and in such instances I will provide the plate with ordinary threaded holes 30, as shown in Figs. 9, 10, and 12, and apply to these holes metal 80 rings 31 of proper thickness to afford the tapered threaded holes 16 and recesses 17, as shown in Fig. 12, for the reception of the glasses 18 and rings 24. The rings 31 will have an external thread to engage the threaded holes 30 in the plate and an annular flange 32 to engage the face of the plate. The rings 31 may be tightly screwed into the plate by means of a spanner engaging the oppositely-disposed recesses 33, formed in the inner face 85 of the rings.

My invention comprises, therefore, in its preferred form a plate having the tapered threaded hole 16 and recess 17 and the glass 18, upon which is locked the externally-threaded tapered ring 24 to engage the said hole 16, the outer end of the glass being adapted at 90 its edges to seat within said recess.

What I claim as my invention, and desire to 100 secure by Letters Patent, is—

1. A plate provided with a tapered and threaded hole and having a recess surrounding said hole, a glass having its outer end of greater diameter than its inner end whereby said outer end is given the form of a head adapted to seat within said recess and said inner end may pass into said hole, and an externally tapered and threaded ring locked upon the body of said glass between its inner end and said head so that said ring and glass 105 may rotate together and said ring be screwed into said tapered and threaded hole; substantially as set forth.

2. A plate having a ring fastened therein and which ring has a tapered and threaded hole and a recess surrounding said hole, combined with a glass having on its outer end a head whose edges are adapted to seat within said recess, and an externally tapered and threaded ring locked upon the body of said glass adjacent to the head thereof and adapted to said tapered and threaded hole; substantially as set forth.

3. A plate provided with a tapered and threaded hole and a recess surrounding the same, a glass having an annular groove around its body and being of greater diameter at its outer than at its inner end whereby said outer end is given the form of a head adapted to seat within said recess and said inner end may 125

pass into said hole, and an externally tapered and threaded ring confined within said annular groove and adapted to said tapered and threaded hole; substantially as set forth.

5 4. A plate provided with a tapered threaded hole and recess surrounding the same, and a glass having an externally-threaded tapered ring fastened thereon and adapted to said tapered hole, the outer end of said glass being adapted to said recess, and said ring being a split ring sprung into an annular groove formed in said glass; substantially as set forth.

15 5. A plate provided with a tapered threaded hole and recess surrounding the same, and a glass having an externally-threaded tapered ring fastened thereon and adapted to said tapered hole, the outer end of said glass being adapted to said recess, and said ring being seated within a groove formed in said glass, and said ring and glass at meeting edges being respectively formed with lugs to engage each other and compel the glass and ring to turn together; substantially as set forth.

25 6. A plate provided with a tapered threaded hole and recess surrounding the same, and a glass having an externally-threaded tapered ring fastened thereon and adapted to said tapered hole, the outer end of said glass being adapted to said recess, and said ring being seated within a groove formed in said glass, and said ring and glass at meeting edges being respectively formed with the recesses and ribs to engage each other and compel the glass and ring to turn together; substantially as set forth.

35 7. A plate provided with a threaded hole, a glass having an annular groove around its body and being of greater diameter at its outer than at its inner end whereby said outer end is given the form of a head and said inner end may pass into said hole, and an externally-

threaded ring fastened in said groove and adapted to said hole, the inner end of said glass having a recess for receiving a key $\frac{1}{8}$ 45 which the glass and ring may be screwed into and from said hole; substantially as set forth.

8. A plate provided with a threaded hole combined with a glass and an externally-threaded ring fastened thereon to engage the walls of said hole, said glass having a head and an inner flanged end and affording an annular groove for said ring, and said ring being a split ring sprung into said groove; substantially as set forth.

55 9. A plate provided with a threaded hole, combined with a glass and an externally-threaded ring fastened thereon to engage the walls of said hole, said glass having a head and an inner flanged end and affording an annular groove for said ring, and said ring being a split ring sprung into said groove, and said glass at its inner end having a recess to receive a key for screwing the glass and ring into said plate; substantially as set forth.

60 10. A plate provided with a threaded hole, combined with a glass and an externally-threaded ring thereon to engage the walls of said hole, said glass having a head and an inner flanged end and affording an annular groove for said ring, said ring being a split ring sprung into said groove, and said ring and glass being respectively provided at their meeting edges with lugs to engage each other and fasten the ring and glass together so that 75 they may be compelled to turn together; substantially as set forth.

Signed at New York city, in the county of New York and State of New York, this 20th day of December, A. D. 1904.
